TOWEL CABINET

Ramuel Morris, St. Louis, Mo., assignor to General Development Company, St. Louis, Mo., a corporation of Missouri

Application June 22, 1938, Serial No. 215,135

3 Claims.

(Cl. 312—38)

This invention relates to improvements in towel cabinets broadly, but more particularly to cabinets wherein a length of toweling is placed within the cabinet in the form of a roll, and is then fed in specified increments from time to time to furnish fresh wiping portions for the successive users, each feeding operation unwinding the toweling from the supply roll and winding up the used toweling onto the used or soiled roll.

One of the objects of my invention is to provide a cabinet of this kind, especially adapted for use in public buildings, large establishments, stores, or in many other places where relatively large numbers of persons may use toilet facilities, and wherein the operating means will be extremely accurate in its winding and unwinding of the toweling, so that there will be no lateral shifting or sidesway of the latter and hence no sticking nor tangling of the toweling to interfere with free rolling thereof.

Another object of the invention is to provide means in a device of this kind, wherein the toweling may be threaded from its fresh or unused roll, passing through and over suitable guide means to its securement to the used roll, and so that the rolling operations that are intermittently given to the toweling will always actuate the toweling in the same longitudinal path and keep the toweling smooth and even during the entire travel of the same.

A further object of this invention is to provide, in a device of the kind described, means for frictionally unwinding the length of toweling from the supply roll and onto the used roll in unison, and in which the toweling is frictionally engaged at a pair of spaced intervals across the width of toweling, this spacing being uniform and constant relative to the side edges of the toweling web throughout the full length of the latter.

An added object of my invention is to provide means cooperating with said frictionally-engaging toweling feeding means, that will increase the effective arc of contact of the toweling with said friction means as the toweling passes over the latter, and hence increase the utility of said friction means.

A still further object of my invention is to provide in a device of the kind described, means actuated by the toweling propelling means, to limit the length of toweling withdrawn from the supply roll at each stroke of the propelling means.

The invention has among its other objects a device of the kind described that shall be neat and attractive in appearance, sanitary in its operation and use, substantially simple and sturdy in construction and operation so as to insure proper working of the same throughout unusually long periods without accidentally getting out of working order, which will be positive in its

operation, and will be otherwise satisfactory and efficient for use wherever deemed applicable.

Many other objects and advantages of the construction herein shown and described will be obvious to those skilled in the art to which this invention appertains, from the disclosures herein given.

To this end, my invention consists in the novel construction, arrangement and combination of parts herein shown and described, and the uses mentioned, as will be more clearly pointed out in the claims hereunto appended.

In the drawings, wherein like reference characters indicate like or corresponding parts throughout the views,

Figure 1 is a front elevation of the cabinet, with parts broken away, in order to show the construction more clearly;

Figure 2 is a side elevation of the same, with the casing in section;

Figure 3 is another side elevation of the device, taken from the opposite side of the same to that shown in Fig. 2;

Figure 4 is a fragmentary sectional detail of the towel guiding plates;

Figure 5 is a fragmentary detail of the towel locking means;

Figure 6 is a perspective detail of the upper feeding roll; and

Figure 7 is a similar view of the lower roll.

Referring more particularly to the drawings, wherein I have illustrated a preferred embodiment of my invention, there is shown a cabinet for successively dispensing fresh portions of toweling upon consecutive operations of the device. Although such cabinets are well-known, they are not always reliable in their operation, on account of the relatively smooth toweling shifting laterally during the feeding travel of the same, and soon getting tangled, twisted, or otherwise clogging up the device so that further operation is prevented until repairs and adjustments have been made to the same.

The device is provided with an exterior casing or cabinet 1, of any desired size, shape and material, but provided with a slot or opening 2 across the lower end thereof and through which the wiping portion of the toweling may depend for use. The casing may be secured to any support, as to an upright wall surface, and into this casing there is inserted the toweling carrier and feeding means. The carrier may consist of a framework of suitable material, as of metal for example, with a pair of spaced side plates 3—3 connected together with an upright back wall 4.

A length of toweling in the form of a roll 5, or supply roll, is adapted to be received in the upper part of the framework, as in a tray or platform 6 placed at a sufficient depth below the top of the framework to accommodate the usual size

roll without interfering with perfect freedom of unrolling or unwinding of the roll. The lowermost or free end of the toweling is adapted to be detachably fastened thereto a carrier roller 7 rotatably mounted below the tray 6 in a pair of slots 8-8 that extend through the sides 3-3 rearwardly for a short distance and thence downwardly and rearwardly, somewhat as shown, such slots permitting ready insertion and removal of the roller 7. As the toweling is used, it is wound onto the roller 7, and in this description will be referred to as the used roll, and when all of the toweling has thus been wound onto the used roll, the latter may be removed together with the roller 7, and a fresh supply roll inserted onto the tray and the exposed end of the second supply roll fastened to the roller 7 removed from the first used roll. Although the length of toweling in the depending loop may be varied to suit the convenience when setting in the toweling for use, I have found it satisfactory to use a loop of about eight inches of toweling, or thereabouts.

One of the great problems in using rolled toweling in cabinets has been the tendency of the toweling to shift, first to one side and then to the other, during the feeding operations, inasmuch as it must be kept in mind that the toweling is relatively soft and smooth. This shifting is quite often sufficient to jam or tangle the toweling against one side or other of the cabinet, and further operation of the device must be halted until repairs and adjustments are made. Therefore, I have provided several means to insure that the travel of the toweling will be in a perfectly straight line between the supply roll and the used roll, and that the feed pull will be uniformly equal on both sides of the center of the toweling, as will now be described in further detail.

A pair of feeding rollers 9 and 10 are arranged in parallel relation across the side plates of the carrier framework, the roller 9 being closely adjacent the supply roll of toweling and over which the toweling travels, and the second roller 10 is positioned within the framework adjacent the lower portion of the latter and rotatably supporting the used roll of toweling, as shown. The pair of rollers 9 and 10 are interconnected by suitable drive means such as the sprocket chain 12, so that they must rotate simultaneously.

In order to maintain uniform pull at either of the side edges of the toweling, and thereby prevent lateral shifting of the latter during travel of the same, I have found it highly effective, not only to suitably roughen the carrier rollers 9 and 10, but in addition have these roughened areas frictionally engage the web of toweling in a predetermined manner. To this end, I space roughened collars 11-11 on one or both of the rollers 9 and 10, the collars 11-11 on the rollers being spaced apart substantially equal distances to either side of the center or median line of the roller, and having their side edges in plane parallel to the side edges of the toweling web, so that as the toweling travels during service, the friction collars, as for example, of sandpaper, will track or draw along the toweling in perfectly straight paths exactly longitudinally of the toweling length.

A weighted bar 13 is mounted to the top of the framework so as to pivot thereto and be supported by the upper roller 9, and it is to be noticed that the vertical plane through the axis of said bar 13 is slightly rearwardly of the cor-

responding plane through the axis of the roller 9, whereby, when the toweling is passed between said bar and roller and extends downwardly from the latter, the arc of contact between the toweling and the friction collars 11-11 is greater than 90°.

Further guides for controlling the path of travel of the web of toweling are provided, as by a pair of upwardly extending plates 14-15, 10 substantially coextensive in width with width of the toweling web, and the former extending across the sides of the framework adjacent the bottom of the latter substantially in front of the roller 10, and the latter plate 15 being pivotally 15 mounted to said framework so as to be moved closely adjacent to said fixed plate and form the narrow slot, passage or guideway 16 therebetween and through which the toweling may be substantially snugly threaded to avoid slack and crumpling between the rolls, or be moved away therefrom for easier threading operations of the toweling therethrough.

Weighted rollers 17 and 18 whose length is substantially coextensive with the width of the toweling web, are movably mounted in the movable guide plate 15 across the top and bottom edges of the same so as to engage the toweling adjacent the top and bottom of the guide slot, respectively, said rollers being mounted in slots extending downwardly and toward the toweling closely adjacent, and whereby the entire weight of the rollers bears against the toweling therealong for substantially the full web of the toweling. The upper and lower edges of the pair of guide plates may be flanged, as at 19 and 20 respectively, the upper weighted roller 17 being slightly above said upper flange, and the lower similar roller 18 being slightly below the lower flange. Side guards in the form of ribs 21-21 46 may be provided to extend upwardly of one of the cooperating guide plates, as for instance on the plate 14, said ribs being spaced apart to conform substantially to the width of the toweling or web to be employed in the device and adapted to bear against one or both of the side edges of the towel web as the latter travels therewith. The other cooperating guide plate, as for example, the plate 15, is provided with a recess to permit the free passage of the ribs therethrough when the plates are closest together in guiding position.

A pull on the exposed portion of toweling depending beneath the cabinet will unwind the toweling from the supply roll, and as it passes over the top feed roller 9 will rotate the latter an amount corresponding to the distance of pull on the toweling, this rotation of the roller 9 transmitting rotation to the roller 10 through the sprocket gearing, and the frictional engagement of the roller 10 and used roll of toweling rotating the latter in a direction to wind up the same in proportion to the amount unwound from the supply roll. The toweling travels upwardly through the passage between the guide plates and in which the side guards or ribs prevent lateral shifting of the toweling and the weighted rollers at the top and bottom of the guide plates smooth out the toweling and assist in preventing any shifting of the toweling.

Sometimes it is desirable to lock the toweling after a predetermined length thereof has been fed to wiping position, so as to prevent waste of the toweling. I have provided a simple means for temporarily locking the toweling after a predetermined portion has been fed into fresh wip-

ing position, the locking being released as soon as the force feeding the toweling has been released. The roller 10 carries a cam 22 adjacent one end, the cam provided with a stop shoulder 23 on its cam surface, and adapted to be slidably engaged by a pawl 24 pivoted intermediate its ends to the framework at 26, so that when the pawl is pivotally moved in one direction it will ride on the cam surface of the cam 22 until the shoulder 23 reaches the pawl, and thereupon continued rotation of the cam is prevented while the pawl remains in latched position. This stops further feeding of the toweling for the time being.

A bar 25 is positioned across the lower portion of the framework, in the path of travel of the web travelling between the rollers 9 and 10, so that the toweling must pass over said bar during its travel to the used roll, and to further insure this engagement of the toweling and bar, a spacer rod 31 may be interposed across the web just above the bar 25 and slightly rearwardly of the latter, so that the toweling rests on the upper edge of the bar 25. The bar 25 is provided with side arms 27-27 pivoted to the side plates of the framework at 28-28, and one of said side arms is extended past said pivot 28 to engage in an elongated recess in the lower end of the pawl 24, this recess being slightly in advance of the pivotal axis on which the pawl is mounted. The initial movement of the arm will first be independently of the pawl, as the elongated slot or recess 29 permits this lost motion or play, but a continued movement of the arm in the same direction will then actuate the pawl about the pivotal axis of the latter and actuate the pawl into cam-bearing position.

Hence, when the towel is grasped from beneath the cabinet, and of course beneath the bar 25, the first portion of the pull will move the bar downwardly together with the toweling, the bar moving a small distance independently of the pawl, on account of the lost-motion between the two, but a continued pull on the toweling will swing the bar 25 further downwardly and the interconnection of the latter with the pawl will swing the pawl into its cam-riding position, in which it will remain during continued movement of the toweling. However, as soon as the toweling has been wound up sufficiently to bring the cam shoulder into the path of the pawl, the parts will become locked against continued movement for the time being, and the operator will then release his pull on the toweling.

A spring 30 is connected between the bar 25 and the framework to retrieve the same to normal position as soon as the pull on the towel is released. As soon as the spring retrieves the bar to its initial position, the pawl shifts away from the shoulder of the cam. A fresh pull will again permit the cam to rotate slightly before the pawl moves into cam-riding position, and will permit a full rotation of the cam before the shoulder is again engaged by and interlocked with the pawl. In the present instance, the pawl is so balanced that it tends to fall away from cam-riding position as soon as the force holding it there is released, but if so desired a spring, (not shown) may be added or substituted to function in the same manner.

Having thus described my invention, it is obvious that various immaterial modifications may be made in the same without departing from the

spirit of my invention; hence I do not wish to be understood as limiting myself to the exact form, arrangement, and construction of the same set forth, except as limited by the state of the art to which this invention appertains and the claims hereunto appended.

What I claim as new and desire to secure by Letters Patent is:

1. In a towel supply device, means to support a supply roll of toweling; means to support a used roll of toweling substantially parallel to said first roll; rolls of toweling supported on said means with a depending loop of toweling between the rolls; means to wind said toweling onto said used roll while unwinding it from said supply roll; and guide means for smoothing said toweling while it is fed comprising a pair of upright plates spaced apart to form a passage therebetween through which the web of toweling passes substantially uniformly snugly from top to bottom of said passage, and rollers rotatably mounted on one plate and bearing against the other plate substantially the full width of the web of the toweling adjacent the upper and lower ends of said passage before and after said toweling passes through said passage.
2. In combination with a used roll and a supply roll of toweling, a towel cabinet, means to support said supply roll of toweling in said cabinet; means to support said used roll of toweling therebelow in said cabinet with a loop of the toweling depending from the cabinet; means to feed said toweling from the supply roll to the used roll; and guide means for smoothing said toweling adjacent said used roll comprising a forward and a rearward upright plate spaced apart for the full width of the toweling web to form an upright passage through which the toweling passes substantially snugly from top to bottom, rotatable rollers mounted on the forward plate constantly bearing against the full web of the toweling and pressing the same toward said other plate adjacent the upper and lower ends of said passage, and guides on said forward plate inclined downwardly and rearwardly toward said last-mentioned plate to receive the ends of said rollers and permit of bodily movement of the latter plate.
3. In combination with a supply roll of toweling and a used roll of toweling, means to support said rolls of toweling; means to feed said toweling from the supply roll onto the used roll; and guide means for preventing lateral shifting of the toweling and for smoothing the same while it is fed to said used roll comprising a pair of spaced upright plates to form a passage through which the web of the toweling passes, said plates being substantially co-extensive in width with the width of said web, and one of said plates having downwardly and rearwardly inclined grooves therein adjacent the ends of said plate, rollers each rotatably mounted on one of said plates and extending across said plates adjacent the upper and lower ends of said passage and having their ends journaled in said inclined grooves to be bodily movable toward the other plate and pressing the toweling against the last-mentioned plate substantially across the full web of toweling, and an edge guide at a side of one of said plates and against which a side edge of said toweling may bear in its travel.
